BARK PEELER HAVING PIVOTED JAWS
SPREAD BY FLUID PRESSURE

Robert E. Burton, Willits, Calif.

Application April 1, 1952, Serial No. 279,838

3 Claims. (Cl. 144—208)

1

This invention relates to devices for peeling logs and particularly to devices of this type which are portable and which are adapted to be used by a single operator at the place where the tree is felled.

In the past it has been the general custom to fell a tree and then transport the same to a mill. The debarking process may take place where the tree falls, where the logs are loaded onto trucks or at the mill, and may be carried out in one of several ways. For example, debarking may be done manually by the use of peeling bars or it may be done mechanically in any one of several well known ways; as illustrated in my copending application Serial No. 190,549, filed October 17, 1950, now Patent No. 2,611,401, dated September 23, 1952.

It is an object of the present invention to provide a manually operated portable bark peeler which may be utilized either at the mill or in the woods, and which will operate in a satisfactory manner for fibrous barked species such as redwood.

It is a further object of this invention to provide a device of this kind which is adapted to be operated by compressed air or hydraulic fluid pressure.

A still further object of this invention is to provide a device of this character which is readily controlled and which reduces physical labor to a minimum and which will work with large, irregular logs which are difficult to rotate or feed by conventional machines.

Other objects and advantages of this invention will appear from the following specification taken in conjunction with the accompanying drawings in which:

Figure 1 represents a top view of my debarking device;

Figure 2 represents a side elevational view of the device in Figure 1 with the jaws of the device in closed position;

Figure 3 is a side elevational view of the device illustrated in Figure 2 with the jaws in open position; and

Figure 4 shows a modification of the device illustrated in Figures 1, 2 and 3.

As illustrated in Figure 1, my device consists of a pair of members 10 and 11 which are pivoted generally at 12. The forward ends 13 and 14 respectively of the two members 10 and 11 operate one above the other and provide surfaces 16 and 17 which, as viewed in Figure 2, form a single planar pointed surface which is adapted to be urged between the wood and the bark.

2

The member 11 is rigidly secured to a frame portion 18 as by means of bolts 19. Frame 18 is in the form of a cylinder 21 and is provided with a reciprocating piston 22 and rod 23 which extends through one end 24 of the cylinder 21. Member 26 is secured to the rod 23 and forms a support for two pairs of rollers 27 and 28. Rollers 28 engage the upper or inner surface 11a of the member 11 and rollers 27 engage the lower or inner surface 16a of the member 10 with the result that when the rod 23 is reciprocated, the members 10 and 11 are urged apart about the pivot 12 with the result that the ends or jaws 13 and 14 are separated.

The means for actuating the piston 22 consists of a source of fluid such as air under pressure which is controlled by a valve 31. An operator, by lever 32, may selectively introduce air through a conduit 33 into one end of the cylinder 21 to urge the jaws 13 and 14 apart (see Figure 3) or through the conduit 34 into the other end of the cylinder 21 to cause the member 26 to be returned to the position generally illustrated in Figure 2. A spring 36 serves to draw the members 10 and 11 together.

A pair of handles 37 and 38 provide means by which the operator may hold the device.

Operation of the device may briefly be described as follows: Let it be assumed that the apparatus is connected to a suitable source of air under pressure through a flexible hose 41 so that the device may be readily moved from one position to another. The operator, by gripping the handles 37 and 38 may urge the closed jaws 13 and 14 into position between the wood and the bark while the jaws 13 and 14 are closed as shown in Figure 2. By operating the hand lever 32 the operator may introduce air into the upper end of the cylinder 21 with the result that the piston 22 will be advanced and the jaws 13 and 14 spread to the position illustrated in Figure 3. The bark and the wood will then be separated. The operator may then actuate the lever 32 in such a manner that air from the upper end of the cylinder is vented and air is introduced into the lower end of the cylinder to return the member 26 to the position illustrated in Figure 2. The spring 36 will draw the members 10 and 11 together or to the position illustrated in Figure 2. Subsequent operations will be the same.

It is apparent from the foregoing that I have provided a simplified device for removing the bark from logs.

The construction of the members 10 and 11 and the jaws 13 and 14 is thought to be unique,

The member 10 is preferably in the form of a flat strip of material and, as illustrated, may be provided with a web portion 42 which lends strength to the entire construction. The member 10 is given a half twist at the point at which the pivot 12 is made to provide a pair of flat surfaces which may be drilled, as indicated in Figure 1, to receive the pin 12. The twist is then completed to provide the jaw 13. Member 11 is similarly twisted to provide jaw 14. The lower surface 10a then becomes the upper surface 13a and the surface 11a becomes the lower surface 14a. This type of construction permits simple fabrication and provides maximum strength at the point 12 where the maximum strain occurs.

In the modification illustrated in Figure 4 the piston 18 and the ram 23 have been eliminated by the use of a piston 43 and a ram 44 which is positioned as indicated for the purpose of separating and drawing together the members 10 and 11. The use of valve 46 for the purpose of controlling the piston 43 is identical with the use of the valve 31 for the purpose of controlling the piston 18. Operation of the device is the same as has been described in connection with the device illustrated in Figures 1, 2 and 3.

I claim:

1. In a debarking device, a pair of controlling levers pivoted to form a pair of jaws adapted to be inserted between the bark and the wood, means for separating said jaws including a fluid ram positioned between the controlling levers of said jaws, and means for controlling said ram in-

cluding a valve to control the supply of fluid under pressure to said ram.

2. In a device of the character described, a pair of flat levers twisted 90° about their longitudinal axes to form cooperating vertical faces and twisted a further 90° about said axes to form cooperating opposed jaws, a pin through said members at the point of said vertical faces forming a pivot about which said jaws may be moved, a fluid ram secured to one of said levers to urge said jaws out of engagement and means for controlling the operation of said ram comprising a valve and a source of fluid under pressure.

3. In a device of the character described, a pair of flat levers twisted about their longitudinal axes to form cooperating vertical faces and further twisted about said axes to form cooperating opposed jaws, a pin through said members at the point of said vertical faces forming a pivot about which said jaws may be moved, a fluid ram mounted upon one of said levers to urge said jaws into and out of engagement and means for controlling the operation of said ram comprising a valve and a source of fluid under pressure.

ROBERT E. BURTON.
